(57) **CLAIM**

The ornamental design for a charger, as shown and described.

DESCRIPTION

FIG. 1 is a front, right and top perspective view of a first embodiment of a charger showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of portion 9 shown in FIG. 1;

FIG. 10 is a front, right and top perspective view of a second embodiment of a charger showing my new design;

FIG. 11 is a rear, left and bottom perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is an enlarged view of portion 18 shown in FIG. 10.

The dash-dash broken lines shown in the drawings depict portions of the charger that form no part of the claimed design. The dot-dash broken lines in the drawing depict boundaries of the enlarged portions that form no part of the claimed design.

1 Claim, 18 Drawing Sheets
